UNITED STATES PATENT OFFICE.

AGNES RAY, OF OAKLAND, CALIFORNIA.

CORSET ATTACHMENT.

1,175,991.

Specification of Letters Patent. Patented Mar. 21, 1916.

Application filed April 22, 1912. Serial No. 692,378.

To all whom it may concern:

Be it known that I, AGNES RAY, a citizen of the United States, residing at Oakland, in the county of Alameda and State of California, have invented new and useful Improvements in Corset Attachments, of which the following is a specification.

This invention relates to corsets and abdominal supporters, its purpose being to provide a combination whereby a corset, with means on its underside, closely and securely attaches to an abdominal band which adequately and comfortably supports the abdomen from beneath, is easy of adjustment by the wearer, counteracts the downward pressure exerted by the ordinary corset, relieves, by its counter upward tension the strain and pull upon the stockings and hose-supporters, and at the same time, is completely concealed beneath the front skirt of the corset—nothing of its presence appearing upon the outside of the corset to distinguish it from the accepted corset of grace and fashion—and is so simple and easy of manufacture as to be an article to be appreciated by both manufacturer and corset-wearer.

The invention is an improvement on the construction disclosed in my prior Patent No. 1,081,197 of July 2, 1912, and consists of the parts and construction and combination of parts as hereinafter more fully described and claimed, having reference to the accompanying drawings, in which—

Figure 1 is a view of the inside of the front of a corset. Fig. 2 is a perspective of the attachment. Fig. 3 shows a modified form of the device.

This invention consists essentially in the combination with a corset of a stiffened, practically diamond-shaped abdominal supporter 2, its upper and lower edges strengthened by a tape 3 or other binding; the lower binding tightened to effect a slight drawing-in of that portion, its length lying across the lower abdomen and entirely concealed beneath the lower front, unstiffened skirt 4 of the corset; its center, vertical width fitted with a perforated steel or bone 5 to which is attached through said perforation by sewing or otherwise at its upper end, a double-eye 6 to engage laterally with hooks one of which is shown at 7 placed on the under side of the corset at the base of the front clasp-steels 8.

The supporter, below its point of juncture 6—7 with the corset is left free to permit its

automatic conformation to the contour of the lower abdomen as the ends, provided with hooks, buckles, studs, or other attaching means 9, are drawn backward and upward to engage with a short anchoring uniting strap 10, complementally provided, and carrying a slide 11 for varying its length and affixed at 12 to the base of the boned section of the corset about six inches back from the front clasp-steels; the means of engagement between the uniting strap 10 and abdominal stay being so placed as not to come in contact with the flesh of the wearer, but turned outwardly against the skirt of the corset.

Various methods of attachment of the supporter to the corset are possible, that one being preferable which offers least impediment to quick and easy fastening by the wearer. The perforated steel or bone 5 extending through the vertical center of the supporter permits the raising or lowering of the double-eye piece 6 should that be necessary to insure a close adjustment to the lower abdomen of the wearer.

A variation of this device is effected, as shown in Fig. 3, by splitting the stay along its central, vertical line, providing the two sections thus formed with hooks and eyes, 85 studs, eyelets for lacing, or other means of connection 13 along the edges so made, and fitting each piece with the front perforated steel or bone 5 and attaching a single eye 6' for engagement laterally with hooks 7 (Fig. 90 1) placed on the underside of the corset-front near the base of the clasp-steels. The laterally engaging hooks on the underside of the corset when united with the double-eye 95 upon the supporter, serve not only to hold the supporter in place, but, obviating the necessity of the customary closing of that part of the front of the corset, hold the two fronts together. The advantages offered by this new arrangement of an abdominal supporter under the front of the unstiffened skirt of the corset, with its attaching means to the corset also affixed beneath the same, are that no part of the device appears upon the surface of the corset to distinguish it 100 from the ordinary corset of custom and fashion; the point of attachment of abdominal supporting band and the anchoring-strap is so far forward and downward as to be within easy reach of the wearer and can 105 be manipulated before or after the corset is fastened, as the entire device lies directly

under the front of the unstiffened skirt of the corset which can easily be lifted either for fastening the band or for readjusting it.

Having thus described my invention, 5 what I claim and desire to secure by Letters Patent, is—

An abdominal supporter for application to the inner side of a corset, comprising a centrally stiffened band separate from the 10 corset and having its lower edge drawn inwardly and made to substantially conform to the groin line of the wearer, being broad at the center and narrow at the ends, flexible, anchoring straps at each end of the band 15 adapted to be connected at their rear ends to the inner side of the corset, adjustable connections between the forward ends of the

anchoring straps and rear ends of the band, and means for attaching the upper portion of the center of the band to the inner side of the corset above the lower edge of the corset and above the horizontal center of the band, whereby the band and adjustable connections are concealed behind the lower portion of the corset and the lower portion of the 25 band will be drawn inwardly and upwardly.

In testimony whereof I have hereunto set my hand in the presence of two subscribing witnesses.

AGNES RAY.
